UNITED STATES PATENT OFFICE.

NELSON H. HENDERSON, OF SYRACUSE, NEW YORK, ASSIGNOR TO SYRACUSE INDUSTRIAL GAS CO., OF SYRACUSE, NEW YORK, A CORPORATION OF NEW YORK

PUMP.

Application filed November 21, 1924. Serial No. 751,278.

This invention has for its object a particularly simple and efficient means for priming pumps, and particularly for priming the pump or centrifugal member on the intake side thereof, which means is particularly simple in construction and highly efficient in use.

The invention consists in the novel features and in the combinations and constructions hereinafter set forth and claimed.

10 In describing this invention reference is had to the accompanying drawings in which like characters designate corresponding parts in all the views.

Figure 1 is an elevation, partly in section of a pump provided with my priming means.

Figure 2 is a plan view of parts seen in Fig. 1.

Figure 3 is a view similar to Fig. 1, of a washing machine embodying my invention.

20 Figure 4 is a sectional view on line 4—4, Fig. 3.

I have here shown my invention as embodied in a dish washing machine of the type described in my pending application Sr. No. 25 698,778, filed March 11, 1924, of which this application is in part a division.

This invention comprises, generally, a casing having an inlet, and an intake pipe extending from the inlet and terminating in the 30 liquid to be pumped, a centrifugal pump arranged in the casing, an outlet arranged at a higher level than the pump, and means for discharging a priming liquid against the pump on the intake side thereof.

35 1 designates the casing which may be of any suitable form, size and construction, it being also a receptacle for receiving the water pumped and to be circulated. In the illustrated embodiment of my invention the casing 1 is formed with an intake opening 2 in

its bottom and with a depending intake pipe 3 for the water to be pumped, this pipe terminating in a receptacle containing the water or fluid to be pumped, as a dish pan, when the 40 machine is used in connection with a dish washing apparatus. The pump is a centrifugal pump and comprises a rotor or pump wheel 4 arranged adjacent the bottom of the casing 1 and coaxially with the intake opening

45 2, the pump wheel having blades 5 on the lower or intake side thereof, which plates project from the lower side of a discoidal body.

Usually the vanes 5 are curved in order to facilitate the centrifugal action.

6 is the outlet opening arranged above the 55 level of the pump wheel 4, this outlet being connected to a discharge pipe through which the water is discharged on to the dishes in the dish pan. A suitable diaphragm 7 may be located between the pump and the outlet 6. 60

The pump wheel 4 is mounted upon a suitable shaft 8 actuated in any suitable manner as in my pending application referred to. It is usually actuated by a motor as 9 arranged at the top of the casing with its axis coincident with the axis of the pump wheel 4, so that, the pump wheel is driven directly by the rotor of the motor. 65

By this construction the upper end of the rotor shaft of the motor is available for a 70 coupling and a flexible shaft for carrying tools as scrubbing tools.

The means for priming the pump is arranged to discharge against the intake side of the pump wheel 4, and as here shown includes a pipe or nozzle 10 terminating in the intake pipe 3 adjacent the intake opening 2, and arranged to discharge against the central part of the pump wheel on the intake side thereof. This nozzle or pipe is connected to 75 a source of supply preferably other than the fluid in the pan or receptacle with which the lower end of the pipe 3 communicates, such source is usually a faucet. Obviously if the pump is actuated it will not initially lift the 80 water up through the empty pipe 3, but by turning on the water to prime the pump, so that, a jet of water is discharged into the fan on the intake side thereof, sufficient suction is created to lift the water from the pan 85 through the intake pipe without first filling up the pipe and submerging the pump wheel. 90

What I claim is:—

1. In a centrifugal pump, a case, a rotor in the case, an unobstructed open inlet pipe arranged coaxially with the rotor and extending downwardly from the case, the case having an outlet above the rotor, a pipe arranged to discharge liquid upon the inlet side of the rotor directly against the rotor for the purpose of evacuating air from the unobstructed inlet pipe and thereby raising the water therein until it reaches the rotor and primes the pump. 100

2. In a centrifugal pump, a case enclosing a chamber having an inlet pipe leading into its bottom, a rotor arranged in the case coaxially with the inlet pipe, the case being formed with a chamber extending circumferentially around the rotor and the rotor arranged relatively to said chamber to discharge throughout its periphery into the chamber, the case having an outlet arranged at a higher level than the rotor and means to discharge a liquid into the rotor on the intake side thereof and directly against the same, the inlet being an unobstructed pipe depending from the bottom of the case.
5. In a centrifugal pump, a casing having an intake opening and an intake pipe through which water is to be pumped connected at one end to said opening, a pump wheel mounted in the casing in line with and adjacent the intake opening, and means for discharging a priming liquid through said intake opening against the pump wheel, the casing having an outlet arranged on the opposite side of the pump wheel to that on which the intake is located.
10. 3. In a centrifugal pump, a case having an open unobstructed inlet pipe at its lower end, a rotor arranged in the case coaxially with the intake pipe and arranged to discharge into the case, the case also having an outlet at a higher level than the rotor and means for discharging water into the rotor to form a water seal in the case above the rotor.
15. 4. In a centrifugal pump, a chamber having an inlet in the bottom, a rotor arranged coaxially with the inlet, the chamber being arranged to drain completely when the pump stops, an outlet for the chamber located at a higher level than the rotor and a pipe con-
- nected with some outside source arranged to direct a stream of water into the rotor directly against the face of the same.
20. 5. In a centrifugal pump, a casing having an intake opening in its bottom, an intake pipe depending from said opening, a centrifugal propeller wheel arranged in the casing coaxially with the intake opening, the casing having an outlet located above the wheel, and means for discharging a priming fluid into the intake opening against the pump wheel.
25. In testimony whereof, I have hereunto signed my name at Syracuse, in the county of Onondaga, and State of New York, this 8 day of November, 1924.

NELSON H. HENDERSON.
